L. PASSANO.
PILOT BURNER.
APPLICATION FILED MAY 1, 1917.

Patented Jan. 25, 1921.

Attorney

UNITED STATES PATENT OFFICE.

LEONARD PASSANO, OF BALTIMORE, MARYLAND, ASSIGNOR TO THE CITIES ILLUMINATING COMPANY, OF NEW YORK, N. Y., A CORPORATION OF NEW YORK.

PILOT-BURNER.

1,366,591.

Specification of Letters Patent. Patented Jan. 25, 1921.

Application filed May 1, 1917. Serial No. 165,679.

To all whom it may concern:

Be it known that I, LEONARD PASSANO, a citizen of the United States, residing at Baltimore and State of Maryland, have invented certain new and useful Improvements in Pilot-Burners, of which the following is a specification.

This invention relates to improvements in pilot burners for lighting gas lamps.

10 The pilot about to be described is of the type shown and described in my application Serial Number 146,389, filed February 3, 1917, or what is termed a "glower" pilot, wherein the glow is designed to keep a considerable area of the mantle in a state of constant incandescence, from which portion, the gas is kindled, without the usual disruptive forces incident to other pilots, but since the present invention does not reside in this feature, it will not be dwelt upon here.

15 The pilot burner about to be described, is especially adapted for use with inverted mantles, and the primary object of the invention is to provide a pilot which, while capable of being maintained sufficiently close to the mantle to produce the proper kindling of the gas, will, at the same time, be capable of being readily moved from normal position to permit the replacement 20 of mantles of the inverted type of burner and to also permit the replacement of shades, when shades are used, and which will in no way interfere with the shades when the shades are in place around the 25 mantles.

30 A further object of the invention is to provide a pilot in which the pressure of the gas for the pilot burner is regulated at a point quite close to the fuel opening, thus 35 getting the advantage of the pressure in the gas main, and rendering the pilot less susceptible to variations of gas pressure.

35 In practice, I have found in the use of pilots either glower or gas flame, that the pilot has to be maintained close enough to the mantle under normal conditions, to kindle the gas when the main flow comes on, and under such conditions, the top of the pilot burner interferes with the ready replacement of shades and mantles.

40 The invention about to be described completely overcomes this disadvantage, and a pilot burner is produced in which, by a very simple manual manipulation, the end of the 45 pilot tube is moved entirely away from the

mantle, giving plenty of room for replacement and adjustment of the mantle upon the burner.

Other objects and advantages of the invention will become apparent in the course 60 of the following description.

In the drawings—

Figure 1 is a front view of the pilot applied to an incandescent gas burner of the inverted type;

65 Fig. 2 is a perspective view of the pilot burner of the double type, designed to light or kindle the gas of two mantles showing one of the pilots in dotted lines, moved to the middle, or to a position where it will not interfere with the replacement of the mantle. Fig. 3 is a partial section of the pilot.

70 Referring to the drawings, the numeral 1 designates two gas burners, which may be of any approved type, and to which is attached mantles 2, both burners being supplied through an ordinary burner tube 3, which may be attached to a gas cock 4, which is of a type well known, and in common use, especially in connection with street lamps, 75 and which embodies a construction in which there is a by-pass which supplies the gas for the pilot light or burner.

75 The numeral 5 designates the pilot tube, which is threaded at its upper end as indicated at 6, for the reception of a double hollow T-union 7 having laterally threaded bosses 8, having channels 9 therethrough, communicating with the chamber 10 of the 80 union.

85 Since the attachments to the union are identical on both sides of the pilot tube, and T-union, a description of one will serve as a 90 description of both.

95 The numeral 11 designates an internally threaded sleeve, of exterior angular formation for the reception of a wrench, by which the sleeve may be adjusted for the purposes that will presently become apparent. Within this sleeve, and having preferably, although not necessarily, a head 12 is a short tube 13, which is threaded or otherwise secured to a hollow connection 14 having bosses 16 and 16' at its upper and lower ends respectively. The tube 13 has a channel 17 100 which establishes communication between the connections 7 and 14. The connection 14 is provided on the inside with a seat 18, for the end of the needle valve 19, the lower portion of which is threaded as indicated at 105 20 110

and passes through a threaded opening in the bottom of the connection, and is provided on the outside with a milled head 21, by which obviously, the valve may be operated to more or less open or close the channel 22, which communicates with the pilot nipple 23, which is provided near its upper end, with a laterally extending fuel outlet 24. Around the top of the nipple, and secured thereto, in any suitable manner, is a wrapping of mantle material 25, or a material capable of being brought to a state of incandescence, or material commonly used for mantle purposes. As above suggested, I prefer to provide the tube 13 with a head 12, which is snugly fitted in the sleeve 17 and permits of gas-tight packing, and the connection is such that when the sleeve 11 is adjusted, the outer end of the member 8 will force the head and packing snugly against the inner walls of the sleeve, thus effectually preventing the escape of the gas, while at the same time, it will be understood that the sleeve adjustment is such as to permit the connection 14, and parts carried thereby, to be rocked in either direction with relation to the fixed pilot tube 5 and T-connection.

The position shown in Fig. 1 is normal position of the pilot nipples wherein they are in vertical position, and in quite close proximity to the mantles for the purpose, as before intimated, of keeping a certain considerable area of the mantles in a state of constant incandescence, but when it is desired to replace a mantle, or a shade, or to do anything else with the burner or mantle, that the exigencies may require, the pilot nipples can be rocked to the position shown in dotted lines, in Fig. 2.

Having thus described my invention, what I claim is:

1. A pilot burner comprising a supply pipe, a hollow member supported at the upper end of said tube, a sleeve threaded on said member, there being an opening in the

end of the sleeve, a tube extending into said sleeve and in communication with said hollow member, a hollow connection carried by the outer end of the tube, a pilot nipple carried by said connection, and having a fuel outlet at its upper end, and means for controlling, within the connection, the flow of gas to the pilot nipple. 50

2. A pilot burner comprising a pilot tube 55 having a hollow connection secured to the top thereof, an adjustable sleeve carried by the hollow member, a tube extending into the sleeve and having communication with the hollow member, a connection carried at the outer end of the tube, a pilot nipple carried by said connection, and having a fuel outlet at its upper end, and a needle valve working within said connection and adapted to control the flow of gas to the fuel nipple. 60

3. In combination with a mantle, a pilot burner comprising a fixed portion through which a supply of gas may be fed, a stuffing box carried by the outer end of the fixed portion and a delivery portion having a 70 headed portion in the stuffing box and normally maintained in close proximity to the mantle, whereby the delivery portion is adapted to be moved away from the mantle, for the purpose described. 75

4. In combination with two vertically disposed spaced mantles arranged in a horizontal plane, a vertically disposed supply pipe adjacent thereto, a cross-head carried by and in communication with the upper end 80 of the pipe, and a vertically disposed pilot burner carried by each end of the cross-head and adapted to swing in a vertical plane so as to bring the pilot burners to or from the mantles. 85

In testimony whereof I affix my signature in presence of two witnesses.

LEONARD PASSANO.
